UNITED STATES PATENT OFFICE.

VICTOR H. CANHAM, OF GUELPH, ONTARIO, CANADA.

DRESSMAKER'S FITTING-TABLE.

No. 913,692.

Specification of Letters Patent.

Patented March 2, 1909.

Application filed May 7, 1908. Serial No. 431,412.

To all whom it may concern:

Be it known that I, VICTOR H. CANHAM, a subject of the King of England, residing at Guelph, in the Province of Ontario, Dominion of Canada, have invented a certain new and useful Improvement in Dressmakers' Fitting-Tables, of which the following is a specification.

My invention relates to dress-makers' fitting tables, and is illustrated in the accompanying drawings, wherein—

Figure 1 is a plan view, Fig. 2 is a side elevation, Fig. 3 is a plan view with the rim removed and parts broken away, Fig. 4 is a cross-section on the line 4—4 of Fig. 3, Fig. 5 is a side elevation, Fig. 6 is a view on the line 6—6 of Fig. 4 looking upwardly, Fig. 7 is a section on the line 7—7 of Fig. 1, Fig. 8 is an enlarged view of the hemmer guide.

Like parts are indicated by the same letter in all the figures.

A A are side pieces of a frame supported on the legs A¹ A¹. B Fig. 3 is a drum mounted on such frame by means of the bearing pieces B¹ Fig. 4, provided with the crank or handle B² and the ratchet wheel B³ and the locking dog B⁴. On the drum are wound chains B⁵ B⁵, two at each end, and each of these chains passes over the pulley C mounted on the frame, down into the chamber C¹ in one of the legs and is attached to the lower end of a rod C², the upper end of which is secured to a movable frame C³ on which is hinged at C⁴ C⁴ the rim C⁵.

C⁶ is a standard which passes through the hole C⁷ in the rim C⁵, and is made fast at C⁸ to parts now to be described which are rigid on the fixed or leg supported rim.

D D Fig. 3 are two bars extending from side to side of the fixed frame and connected to the side pieces A A.

D¹ is a part fastened to one of the bars D to make the bearing C⁸ for the bar C⁶.

D² Fig. 4 is a shorter and lower cross bar extending from the side piece A to the side piece A.

D³ D³ Figs. 3 and 7 are two sliding bars which lie outside of the bars D D passing through slots at D⁴ D⁴ in the bars A connected together at their outer ends by a cross piece D⁵ and at their inner ends by the cross piece D⁶ which lies below the bars D D and above the bar D².

E is an extension table which has the downwardly projecting guide bars E¹ E² which serve to bring the table E into posi-

tion at rest upon the bars D³ D³, when they are extended as shown in the dotted lines in Fig. 3.

F F Figs. 1 and 2 are short bars secured 60 on the surface of the rim C⁵ overhanging the groove F¹ in which slides the base F² Fig. 8 of the hemmer guide which consists of the upwardly extending part F³ and the arc-shaped portion F⁴. The hemmer guide base 65 can be moved in or out, adjusted to the position of the skirt, and it is locked in such predetermined position by the set screw F⁵.

The rim being hinged at C⁴ C⁴ to a movable frame which consists of the bars C³ is adapted 70 to be tilted as shown in Fig. 5. The movable frame is supplied with the cross bars G G Fig. 6 and the corner strengthening bars G¹ G¹. Between the bars G G and pivoted thereto lies the rim support consisting 75 of the two legs G² G² connected by the cross piece G³, pivoted at G⁴ to the bars G G and held from too great extension by the chain G⁵ as indicated in Fig. 5.

H is a fixed platform mounted on the bars 80 D D.

J is a spiral spring or elastic device secured to the bar D² at one end, and to the chain J¹ at the other. This chain passes around the shaft J² mounted on the supports J³ J³ which are secured to one of the fixed frame pieces A. On the shaft J² is the drum J⁴ on which is wound the measuring tape J⁵, the other end of which is secured to the bar C³ of the movable frame on which 90 the rim is mounted.

While in my drawings I have illustrated an actual construction, I wish nevertheless to have them taken as diagrammatic, and merely intended to illustrate my invention 95 to show its construction in a concrete form.

The use and operation of my invention are as follows:—The person to be fitted stands on the fixed platform H. If the skirt has a train, the sliding frame can be drawn out as 100 shown in Fig. 3, and the extension platform be laid thereon. The rim can now be adjusted to any height by operating the crank B² whereby the movable frame and rim mounted thereon will be elevated. The rest 105 standard C⁶ is in a vertical position, and since it passes through the perforation in the rim, it remains undisturbed. The height to which the rim is elevated is determined and easily adjusted by reference to the tape J⁵ 110 which is elastically held to the fixed frame and is connected at its end to the movable

frame. The hemmer guide can be moved back and forth into any desired position to accommodate itself to the circumstances. When the table has served its purpose as a fitting and hemming measuring table, it should serve some useful purpose or otherwise it takes up a great deal of valuable space in the ordinary shop. For that reason I have provided a tilting rim. The rest standard is removed, the extension platform is removed, the sliding frame is pushed into position and the movable frame can then be raised to any desired height and the rim can then be tilted thereon and held in position as shown in Fig. 5, and the device then becomes a display stand.

To limit the upward movement of the rim I provide a chain K wrapped around the drum B and secured thereto at one end and secured at the other end to a projection K¹ from the rim or frame. The length of the chain limits the upward movement.

I claim:

1. In a dress-maker's fitting table, the combination of a fixed frame with a movable frame, and a fixed platform on the fixed

frame, and a rim hinged on the movable frame so as to be tilted thereon, and moved therewith, and a folding support on such tilting rim on the side opposite the hinges.

2. In a dress-maker's fitting table, the combination of a fixed frame with a movable frame, and a fixed platform on the fixed frame, and a rim on the movable frame and a hemmer guide mounted on the rim.

3. In a dress-maker's fitting table, the combination of a fixed frame with a movable frame, a fixed platform on the fixed frame, and a rim on the movable frame and a hemmer guide mounted on the rim so as to be adjustable toward and from the fixed platform.

4. In a dress-maker's fitting table, the combination of a fixed frame with a movable frame, a fixed platform on the fixed frame, and a rim on the movable frame and a sliding frame on the fixed frame and a removable extension platform adapted to rest on such sliding frame.

VICTOR H. CANHAM.
